Primary Examiner — S. Bryan Reinholdt, Jr.*Assistant Examiner* — James T Tyree(74) *Attorney, Agent, or Firm* — DeLio Peterson & Curcio LLC; Brian G. Schlosser(57) **CLAIM**

The ornamental design for a toy car, as shown and described.

DESCRIPTION

FIG. 1 depicts a side perspective view of the toy car according to my design;

FIG. 2 depicts a right side elevational view of the toy car shown in FIG. 1;

FIG. 3 depicts a left side elevational view of the toy car shown in FIG. 1;

FIG. 4 depicts a top plan view of the toy car shown in FIG. 1;

FIG. 5 depicts a bottom plan view of the toy car shown in FIG. 1;

FIG. 6 depicts a front elevational view of the toy car shown in FIG. 1; and,

FIG. 7 depicts a rear elevational view of the toy car shown in FIG. 1.

The broken lines and the areas within them in FIGS. 1 through 5 depict portions of the toy car that form no part of the claimed design.

1 Claim, 7 Drawing Sheets(56)
